DESIGN FOR A PROGRAM CLOCK

Hugh W. Sanford, Knoxville, and Fritz H. Thomas, Greeneville, Tenn., assignors to Program Clock, Inc., Knoxville, Tenn., a corporation of Tennessee

Application September 9, 1932, Serial No. 44,786

Term of patent 14 years

To all whom it may concern:

Be it known that we, HUGH W. SANFORD and FRITZ H. THOMAS, citizens of the United States of America, residing respectively at Knoxville, in the county of Knox, State of Tennessee, and Greeneville, in the county of Greene, State of Tennessee, have invented a new, original, and ornamental Design for a Program Clock, of which the following is a specification, reference being had to the accompanying drawing, forming part thereof, in which

Figure 1 is a front elevational view of a program clock showing our new design; and

Figure 2 is a side elevation of the same, on a somewhat reduced scale.

We claim:

The ornamental design for a program clock as shown.

In testimony whereof we subscribe our signatures.

HUGH W. SANFORD.
FRITZ H. THOMAS.
